Primary Examiner — Dana K Weiland*Assistant Examiner* — Russell Carnell Smith, Jr.(74) *Attorney, Agent, or Firm* — Young Basile Hanlon & MacFarlane, P.C.(57) **CLAIM**

The ornamental design for an IP access control device, as shown and described.

DESCRIPTION

FIG. 1 is a front view of an IP access control device of my new design;

FIG. 2 is a left side elevation view thereof, with the right side being a mirror image thereof;

FIG. 3 is a top view thereof; and,

FIG. 4 is a bottom view thereof.

The dash-dash broken lines represent portions of the IP access control device and form no part of the claimed design.

1 Claim, 2 Drawing Sheets(56)
